AUTOMOBILE FENDER GUIDE

William B. Sandler, Newton, Mass.

Application January 29, 1954, Serial No. 28,717

Term of patent 14 years

(Cl. D14—6)

FIG. 1

I claim:

The ornamental design for an automobile fender guide, as shown.
